UNITED STATES PATENT OFFICE.

FRANK J. FEHN, OF EAST ORANGE, NEW JERSEY, ASSIGNOR TO THE WHITEHEAD & HOAG COMPANY, OF NEWARK, NEW JERSEY, A CORPORATION OF NEW JERSEY.

BADGE-FASTENER.

1,386,096.

Specification of Letters Patent.

Patented Aug. 2, 1921.

Application filed April 10, 1919. Serial No. 288,911.

To all whom it may concern:

Be it known that I, FRANK J. FEHN, a citizen of the United States of America, and resident of East Orange, in the county 5 of Essex, in the State of New Jersey, have invented new and useful Improvements in Badge-Fasteners, of which the following, taken in connection with the accompanying drawings, is a full, clear, and exact description.

This invention relates to certain improvements in badges and similar articles having hinged pins by which they may be removably attached to a garment and refers more particularly to the means for supporting and locking the pin upon the main body or back of the badge.

The means commonly employed for mounting the pin upon the badge-plate and for locking it in closed position consists of ears or lugs made separate from the plate but secured thereto by soldering or similar fastening means which, aside from the necessity for making these pieces from extra stock, are more or less insecure and, therefore, unreliable, and the main object of my present invention is to stamp these parts from the pin-supporting plate and thereby to produce a stronger, more permanent and reliable pin fastening, but also to enable those parts to be formed in practically the same operation which forms the main body of the pin-supporting plate or badge.

Other objects and uses relating to specific parts of the badge will be brought out in the following description.

In the drawings:

Figure 1, is a rear face view of one form of badge plate showing the pin-supporting and locking ears or lugs in operative position and the pin as attached thereto.

Fig. 2, is a face view of the same pin-supporting plate shown in Fig. 1, omitting the pin, the pivot supporting lugs and locking member or keeper being shown as flattened out or in the position in which they are cut before bending to receive the pin.

Fig. 3, is an enlarged sectional view taken on line 3—3 Fig. 1.

Figs. 4 and 5, are detail sectional views taken on lines 4—4 and 5—5 Fig. 1.

Fig. 6, is a rear face view of a modified form of pin-supporting plate having integral pivot-supporting lugs and keeper similar to that shown in Figs. 1 to 5, inclusive.

Fig. 7, is a face view of the pin supporting plate shown in Fig. 6, except that the lugs and keeper are flattened out as originally cut before bending.

Figs. 8 and 9, are detail sectional views 60 taken respectively on lines 8—8 and 9—9 Fig. 6.

The pin supporting plate as —1— may be of any desired size or form but is preferably made of thin sheet metal and has portions thereof cut in the form of tongues integral at one end with the body of the plate so that they may be folded or bent in the same direction and in parallelism to form a pair of ears or lugs —2— for receiving between them one end of a pin —3—, said lugs and interposed portion of the pin being apertured to receive a pivotal rivet —4—.

Another portion of the pin supporting plate some distance from the pivot receiving 75 lugs —2— is cut from the main body in the form of a hook shaped tongue —5— integrally united at one end to said body and afterward bent up to a plane at substantially right angles to said body to form a 80 keeper or locking member with which the free end of the pin —3— may be interlocked and released at will, the open side of the keeper hook —5— facing the main body of the plate while the free end of the hook is 85 spaced a sufficient distance from said body to permit the point of the pin to pass between those parts into and out of the open side of the keeper.

The pivotal end of the pin —3— is also 90 hook shaped in that it is returned a short distance in the same direction as the main body to form a supplemental arm —6—, the free end of which is spaced a sufficient distance from the main portion of the pin to 95 permit it to be hooked over and upon the pivot —4— as shown more clearly in Fig. 3.

The relation of this supplemental arm —6— to the main portion or shank of the pin is such as to cause it to impinge against 100 the adjacent face of the plate —1— with a resilient motion when the point of the pin is forced into interlocking engagement with the keeper —5— to yieldingly hold said pin in its closed or locked position.

That is, the pin is preferably made of resilient wire so that when forced to its locking position, its supplemental arm —6— will be placed under more or less tension tending to open the pin when released and to 110

tension it against the under side of the keeper when closed, which together with the rigidity of the lugs —2— and —5—, by reason of their integrity with the main body 5 of the plate, affords a stronger, and, therefore, more efficient means of attaching the badge to a garment.

What I claim is:

In a badge fastener, the combination of a 10 sheet metal plate having integral ears and an integral keeper hook pressed up to one side of the main body, said ears projecting edgewise from the main body in spaced parallel planes, the keeper hook projecting edge- 15 wise from said body in a plane at right angles to that of the ears, a pintle between and

upon the ears, a pin looped around the pintle and having its ends extending in the same general direction therefrom, one end being movable into and out of engagement with the 20 hook, and the other end being movable into and out of engagement with the main body of the plate at a point between the pintle and hook and placed under tension when the pin is engaged with the hook. 25

In witness whereof I have hereunto set my hand this 21st day of March, 1919.

FRANK J. FEHN.

Witnesses:

GEORGE E. POST,
FREDRICK FEHN.
